Primary Examiner — Manpreet S Matharu*Assistant Examiner* — Keith J Wilson(74) *Attorney, Agent, or Firm* — Shaukat A. Karjeker;
Carstens & Cahoon, LLP(57) **CLAIM**

The ornamental design for a filter, as shown and described.

DESCRIPTION

FIG. 1 is a front perspective view of the present invention;
 FIG. 2 is a front elevation view of the present invention;
 FIG. 3 is a rear elevation view of the present invention;
 FIG. 4 is the right side view of the present invention;
 FIG. 5 is the left side view of the present invention;
 FIG. 6 is the top view of the present invention; and,
 FIG. 7 is the bottom view of the present invention.
